CLAIM

The ornamental design for a chemical analysis instrument, as shown and described.

DESCRIPTION

FIG. 1 is a front left top perspective view of a chemical analysis instrument;

FIG. 2 is a front right top perspective view of the chemical analysis instrument of FIG. 1;

FIG. 3 is a back right bottom perspective view of the chemical analysis instrument of FIG. 1;

FIG. 4 is a front elevation view of the chemical analysis instrument of FIG. 1;

FIG. 5 is a back elevation view of the chemical analysis instrument of FIG. 1;

FIG. 6 is a left elevation view of the chemical analysis instrument of FIG. 1;

FIG. 7 is a right elevation view of the chemical analysis instrument of FIG. 1;

FIG. 8 is a top elevation view of the chemical analysis instrument of FIG. 1; and,

FIG. 9 is a bottom elevation view of the chemical analysis instrument of FIG. 1.

The broken lines shown are included for the purpose of illustrating portions of the chemical analysis instrument that form no part of the claims.

1 Claim, 9 Drawing Sheets
